UNITED STATES PATENT OFFICE.

HENRY FLYNT, OF KANSAS CITY, MISSOURI, ASSIGNOR OF ONE-HALF TO
CHARLES E. COOK, OF SAME PLACE.

OVEN FOR VAPOR-STOVES.

SPECIFICATION forming part of Letters Patent No. 378,301, dated February 21, 1888.

Application filed April 18, 1887. Serial No. 235,269. (No model.)

To all whom it may concern:

Be it known that I, HENRY FLYNT, of Kansas City, Jackson county, State of Missouri, have invented certain new and useful Im-
5 provements in Vapor-Stove Ovens, of which the following is a full, clear, and exact description, reference being had to the accompanying drawings, forming a part hereof.

This invention relates to ovens for use upon 10 vapor or gas stoves; and it consists in the peculiar features and combination of parts, more fully described hereinafter, and pointed out in the claims.

In the drawings which illustrate the manner 15 of carrying out my invention, Figure 1 is a front elevation of the oven. Fig. 2 is an end view showing the door down in dotted lines. Fig. 3 is a plan view of the oven. Fig. 4 is a section through the oven on line α α ; Fig. 3. 20 Fig. 5 is a detail section showing the construction of the door. Fig. 6 is a front view of the door. Fig. 7 is a section through the door shown in Fig. 6, the section being taken on line y y . Fig. 8 is a detail view of a portion of the 25 outer shell of the oven, showing the manner in which the sheets are to be bent at the corners. Fig. 9 is a detail view of the edge of a sheet forming the shell of the oven, and showing the form of the strengthening-flange formed 30 thereon; and Fig. 10 is a perspective view of the oven with the door in a horizontal position.

A indicates the outer shell of the oven, which is of the usual rectangular shape, but comparatively much less in height than the ordinary oven, and B is the lower portion of the oven, constructed with inclined sides, as shown, and provided with cast foot-piece B'. This foot-piece has a curved portion, 3, removed from the outer edge of each of its sides, 40 thereby forming a supporting-foot at each of its corners, as shown.

It will be observed that the oven A is constructed, practically, without the usual bottom sheet, and that the flame from the burner, 45 together with the outer air, is free to enter its open bottom 2, whence, after coming in contact with the deflector B", it will pass up around the back of the oven, over and among the shelves C, and then downward in the front

and out of a series of apertures, 4, (one or 50 more,) formed in the inclined portion B.

The oven A should be provided with an interior lining of tin in any desired way, and the deflector B" should be secured to the front plate of the inclined portion B so that its inner edge will be inclined upwardly, as shown. 55

The oven should be provided with lifting-handles at opposite ends, such as 50, so that it can be easily removed from the stove when required, and a suitable hook, such as 51, 60 should be pivoted to the back plate of the inclined portion B for engaging with the grating of the stove-top to keep the oven from tilting forward when a heavy weight is placed on the door when the latter is in a horizontal position. Said hook will have a sufficient length to extend some distance below the feet of base B' and engage with the grating below them. 65

The door D is composed of a cast-iron frame, J, which is provided with an upwardly-projecting lug, a', at its upper side for engaging a hook, a, pivoted to the top of the oven and held in place by a strap, a"; still any other form of fastening for holding said door in a closed position may be employed. In addition to the lug a', the frame J is provided with lugs E" at opposite sides, which may either be cast integral with it or riveted thereto, as preferred. 70

Arms E are pivoted at their lower ends to 80 opposite sides of the oven, and are provided with a slot, E', near their upper ends, which is engaged by lugs E" on the door. Said arms are adapted to rest upon lugs F, which are located just below them, when in a horizontal 85 position, and so support the door at all times, except when in a closed position.

It will be observed that the lugs E" loosely engage the slots in the supporting-arms and slide therein during the operation of opening 90 and closing the door, and that said arms loosely support said door in opening and closing the same, as the weight thereof is thrown on said slots during such operation.

A bar or rail, G, which is preferably of 95 wood to prevent heating, extends across the front of the oven and connects the arms E together at their upper ends. This rail may be

utilized as a towel-rack to hang cloths upon; but its primary object is to operate as a handle for the door in operating same. If desired, an additional handle, such as *b*, can be 5 secured to said rail.

The frame *J* of the door is provided with hinge-lugs *e* at opposite ends, which engage suitable apertures in lugs *F*, thereby forming a complete hinge for said door.

10 My preferred construction of the oven-door is as follows: The frame *J* is of cast metal and rectangular in general contour and provided with a panel composed of two sheets of metal, an outer sheet of Russia iron and an inner 15 sheet of tin. I proceed to place such panel in the door by turning up three edges of the outer sheet, so as to form a hollow flange, 30, for the reception of another flange, 32, formed on corresponding edges of the inner sheet, 20 causing the flange 32 to engage the hollow flange 30, then locating said hollow flange on the outer surface of said frame *J* and turning the edge 31 of the outer sheet down upon the inner surface of said frame, and, lastly, securing 25 the corresponding edges of the sheets that have not been flanged to the frame by means of rivets, as shown more clearly in Fig. 7.

The shell of the oven is constructed from a single sheet of metal and its corners are sufficiently stiffened by the construction shown in 30 Figs. 8 and 9. In these figures the shell *A*, which extends around the oven, is provided with a rectangular flange or bead, 5, and at each corner a triangular portion, 75, is removed from the said flange, and apertures 6, 35 which are adapted to register when the sheet is bent, are formed in the flange near the recess formed by removing the triangular piece. After said sheet is bent to the proper form a 40 rivet is passed through said apertures and secures the parts in the position desired.

If so desired, I may construct the door *D* with its panel-sheets secured to the frame entirely by rivets, as indicated in Figs. 6 and 7, 45 the line of rivets extending entirely around the door.

It should be clear that my construction of the lower portion of the oven with flaring or inclined sides is an important part of my invention, as the space between the burner and 50

the shelves is thereby much reduced in volume and the free use of the burner next adjacent to the oven is also permitted. Heretofore, with an oven of sufficient size to be of value to the general housekeeper, this could not be accomplished, as the oven would partly cover the space on the stove-top devoted to the other burners, and said burners could not well be used while the oven was on the stove. 55

With the improved construction of the oven 60 here shown, the bottom of the oven is much reduced in size and is restricted to a single burner on the top of the stove, thereby permitting other utensils—such as a skillet or pan—to be placed partly beneath the body of 65 the oven.

Having thus described my invention, what I claim is—

1. In an oven for vapor-stoves, the outer shell, *A*, provided with a contracted portion, 70 *B*, having an open bottom and oblique walls, and provided with apertures 4, in combination with a deflector, *B*', extending partly across the contracted portion and secured thereto at a point below said apertures, in the manner 75 and for the purpose substantially as described.

2. In an oven for vapor-stoves, the combination of the outer shell, *A*, the door *D*, hinged thereto and provided with slotted arms *E*, hinged to said shell upon opposite sides of 80, said door, the lugs *E*', operating within said slots, the bar *G*, connecting the free ends of said arms, the lugs *F*, forming a rest for the arms, and the attaching-hook 51, located upon the side of the oven opposite the door, all 85 adapted to operate as described.

3. In an oven for vapor-stoves, a door provided with a pair of arms hinged to the oven upon opposite sides of the door, said arms being provided with curved slots and a cross-bar at their free ends, in combination with lugs upon the door operating within said slots, and supporting-lugs forming hinges for the door, substantially as described. 90

In testimony whereof I affix my signature in 95 presence of two witnesses.

HENRY FLYNT.
